(57) **CLAIM**

The ornamental design for a roll threader tool, as shown and described.

DESCRIPTION

FIG. 1 is a top, perspective view of a first embodiment of a roll threader tool, according to our new design;

FIG. 2 is a front view thereof;

FIG. 3 is a rear view thereof;

FIG. 4 is a right view thereof;

FIG. 5 is a left view thereof;

FIG. 6 is a top view thereof;

FIG. 7 is a bottom view thereof;

FIG. 8 is a bottom, perspective view thereof;

FIG. 9 is a top, perspective view of a second embodiment of a roll threader tool, according to our new design;

FIG. 10 is a front view of FIG. 9;

FIG. 11 is a rear view of FIG. 9;

FIG. 12 is a right view of FIG. 9;

FIG. 13 is a left view of FIG. 9;

FIG. 14 is a top view of FIG. 9;

FIG. 15 is a bottom view of FIG. 9; and,

FIG. 16 is a bottom, perspective view of FIG. 9.

The portions shown in broken lines form no part of the claimed design.
